(57) **CLAIM**

The ornamental design for a clamp ring with eyelets, as shown and described.

DESCRIPTION

FIG. 1 is an isometric view of a clamp ring with eyelets, showing our new design;

FIG. 2 is another isometric view of the clamp ring with eyelets shown in FIG. 1;

FIG. 3 is a left side elevational view of the clamp ring with eyelets shown in FIG. 1;

FIG. 4 is a right side elevational view of the clamp ring with eyelets shown in FIG. 1;

FIG. 5 is a front elevational view of the clamp ring with eyelets shown in FIG. 1;

FIG. 6 is a rear elevational view of the clamp ring with eyelets shown in FIG. 1;

FIG. 7 is a top plan view of the clamp ring with eyelets shown in FIG. 1; and,

FIG. 8 is a bottom plan view of the clamp ring with eyelets shown in FIG. 1.

The broken lines shown in the Figures are included for the purpose of illustrating portions of the clamp ring with eyelets that form no part of the claimed design.

1 Claim, 6 Drawing Sheets
